UNITED STATES PATENT OFFICE.

ZOTIQUE BEAUDRY, OF LYNN, MASSACHUSETTS, ASSIGNOR TO HAMEL SHOE MACHINERY CO., INC., OF LYNN, MASSACHUSETTS, A CORPORATION OF MASSACHUSETTS.

SOLE-EDGE-BURNISHING MACHINE.

1,162,438.

Specification of Letters Patent. Patented Nov. 30, 1915.

Application filed January 10, 1914. Serial No. 811,469.

To all whom it may concern:

Be it known that I, ZOTIQUE BEAUDRY, a citizen of the United States, residing at Lynn, in the county of Essex and State of Massachusetts, have invented new and useful Improvements in Sole-Edge-Burnishing Machines, of which the following is a specification.

This invention relates to a machine for setting and burnishing the edges of the soles of boots and shoes and for corrugating the upper edge portion of said sole.

The invention relates particularly to that class of edge setting or burnishing machines for which Letters Patent of the United States No. 931,538 were issued to me August 17, 1909, and embodies an improved presser foot in connection with the edge burnishing irons, whereby the work may be easily and accurately held in position, and which particularly assists in the burnishing and corrugating of the edge of the sole simultaneously, a corrugating wheel being employed on the fore part iron to bear against the upper edge of the sole while the fore part is being set or burnished.

The invention, moreover, relates to improved details of construction of the mechanism whereby the fore part edge burnishing iron and the shank burnishing iron are substituted alternately, one in place of the other, without the operator being obliged to take either hand away from the shoe in order to operate said mechanism.

Still further the invention relates to improved details of mechanism whereby the knee lever which operates the fore part edge and shank iron reversing mechanism is rendered practicable and convenient.

The invention consists in the combination and arrangement of parts set forth in the following specification and particularly pointed out in the claims thereof.

Referring to the drawings: Figure 1 is a front elevation of my improved edge burnishing machine. Fig. 2 is a left hand side elevation of the machine. Fig. 3 is a right hand side elevation of the machine. Fig. 4 is a plan view of the machine, certain portions of Figs. 1 to 4 inclusive being broken away to save space in the drawings. Fig. 5 is a plan view of the knee lever mechanism. Figs. 6 and 7 are plan views of different positions of the mechanism whereby the edge setting tools are rotated. Fig. 8 is a

sectional elevation taken on line 8—8 of Fig. 6. Figs. 9, 10, and 11 are detail views illustrating modified forms of presser foot in connection with a sectional view of a shoe in position relatively to the edge burnishing iron and said presser foot.

Like numerals refer to like parts throughout the several views of the drawings.

The machine illustrated in the drawings is designed to be used as a double machine, that is, with a complete mechanism for burnishing the edges of the soles of boots and shoes on opposite sides thereof respectively, the mechanism for such burnishing, however, only being shown on one side of the machine in the drawings.

In the drawings, 10 is the main driving shaft driven by a pulley 11 and belt 12. An eccentric pin 13 is formed upon the end of the shaft 10 and upon this eccentric pin is mounted an eccentric connection 14 which fastened to and forming, in effect, a portion engages at its free end an arm 15 rigidly of a rocker frame 16.

The rocker frame 16 is mounted to rock upon a stationary shaft 17 fast to the frame 18 of the machine. The rocker frame 16 has a downwardly extending arm 19 and on said arm is rotatably mounted a tool carrier 20 consisting of a vertically extending shank 21 journaled to rock in a bearing formed in said arm 19 and a cross-bar 22 to which are attached the fore part burnishing iron 23 and the shank burnishing iron 24. The fore part burnishing iron 23 has a corrugating tool 25 rotatably mounted thereon.

The details of construction of the fore part and of the shank burnishing irons and of the corrugating tool are substantially the same as those illustrated in my copending application Serial No. 642,147.

The shank 21 has a collar 26 fast to its upper end and is connected to a spindle 27 by a flexible connection 28, preferably consisting of a helical spring. The spindle 27 is rotatably and slidably mounted in the frame of the machine and has fastened thereto a pinion 29 by means of which it may be rotated. A friction roll 30 is journaled to rotate in the upper end of said spindle. A spring 31 encircles the spindle 27 and is contained within a recess 32, while its upper end bears against the hub of the pinion 29 and its lower end bears against the bottom of said recess. The tendency of

said spring is to hold the spindle 27 and its pinion gear 29 upwardly, with the cross-bar 22 seated in a recess 33 in the under side of the arm 19.

5 When it is desired to change one of the burnishing irons for the other, the spindle 27 is pushed downwardly and rotated, so that the cross-bar 22 is pushed out of the recess 33 and the tool carrier 20 is rotated to place one of the burnishing irons in the position formerly occupied by the other. The spindle is then released and is carried upwardly to seat the cross-bar 22 in the recess 33. This change of position of the burnishing irons is accomplished by means of a lever 34 which is pivoted on a stud 35 fast to the frame of the machine and normally held in the position illustrated in Fig. 3 by a torsional spring 36. This torsional spring 20 has one end thereof fast to said lever and the other end fast to a collar 37 rotatably mounted upon the stud 35, whereby more or less tension can be placed upon said spring.

A sleeve 38 is rotatably mounted upon the lever 34 and is fastened thereto by means of a hand nut 39. An arm 40 extends laterally from the lever 34 and is pivoted to the sleeve 38 at 41. The sleeve 38 bears at its lower end against a collar 42 fast to the lever 34, whereby said sleeve is prevented from sliding longitudinally of the lever 34 in a downward direction, but can be adjusted to any desired height thereon by raising and lowering said collar 42 which is fastened to the rod by a suitable set-screw.

40 A knee piece 43 is fastened by a hand screw 44 to the arm 40. A flexible member, preferably a chain 45, is fastened at its upper end to the sleeve 38 and at its lower end to a collar 46 fast to the arm 40. This collar is adjustable on the arm 40 whereby said arm may be set at different angles relatively to the lever 34 and thus the knee piece 43 may be raised or lowered, as desired.

45 A spring 47 is fast to the collar 46 and thus to the arm 40 at one end thereof and at the other end thereof is fastened to a collar 48 which, in turn, is adjustably fastened to the sleeve 38.

50 By changing the position of the collar 42 on the lever 34 the arm 40 and sleeve 38 may be moved upwardly or downwardly on said lever, as may be desired. By changing the position of the collar 46 on the arm 40 the angle at which said arm stands to the sleeve 38 may be changed.

When in use the arm 40 can be tipped by the knee of the operator while manipulating the lever 34, while the spring 47 always returns said arm to its normal position. When the machine is not being used the arm 40 may be swung out of the way back against the frame of the machine by loosening the set-screw 39 and rotating the sleeve 38 upon 65 the lever 34.

The lever 34 is pivotally connected at its upper end at 49 to a holder 50 which, in its turn, is pivoted to a stud 51 fast to a slide 52. Said slide has ears 53 thereon adapted to slide on parallel rods 54 fastened 70 to the frame 18. A cam-shaped finger 55 is fastened to the holder 50 and said holder has an ear 56 extending downwardly therefrom at one side of the U-shaped slide 52. On the opposite side of said U-shaped slide 75 is another ear 57 fast to the holder 50.

Normally the torsional spring 36 holds the lever 34 in the position illustrated in Figs. 2 and 4, with the ear 57 bearing against the slide 52. When the lever 34 is 80 rocked by pressing the knee against it so as to bring the upper end of said lever toward the front of the machine the holder 50 is rocked from the position illustrated in Fig. 4 to that illustrated in Figs. 6 and 8 and 85 the ear 56 then bears against the slide 52. Upon further movement of the lever the slide 52 moves forward and the cam-shaped finger 55 engages the roll 30 and pushes the spindle 27 downwardly, together with its 90 pinion 29, until the pinion 29 is in alignment with a rack 58, said rack 58 being fastened to said slide 52. At the same time the spindle, through the flexible connection 28, moves the tool carrier 20 downwardly until the 95 cross-bar 22 is moved out of the recess 33 and the spring 28 then rotates the tool carrier 20 until the burnishing tool, which was formerly in position to operate upon the edge of the sole of the shoe, is replaced by the other of said burnishing tools—that is, the tool 24 will take the place of the tool 23 and vice versa.

When the cam-shaped bend 59 in the finger 55 has passed the roll 30 the spindle 27 will be forced upwardly by the spring 31 and upon releasing the knee lever the rack 58 and the holder 50, together with the cam-shaped finger 55, will return to the position illustrated in Fig. 4. In Fig. 7 the parts 100 just referred to are shown in the position they occupy when the slide 52 is in its forward position.

Collars 60 encircling the rods 54 form stops to limit the distance to which the slide 52 can be moved forward and springs 61 encircling the rods 54 constitute spring buffers against which the slide 52 strikes at the end of its rearward movement.

A pin 62 is mounted to slide vertically in 115 the rocker frame 16 and projects into the recess 33 in which the cross-bar 22 of the tool carrier 20 is located. The lower end of this pin bears against the upper edge of said cross-bar and is in alignment with the 120 particular burnishing tool which is in position for operating upon the edge of the sole of the shoe. Said pin is held with a yielding pressure against the cross-bar 22 by a spring 63 which is forced against the pin 62 130

with greater or less pressure by means of a screw 64 having screw-threaded engagement with the rocker frame 16 and bearing at its lower end against the upper end of the spring 63. The function performed by this spring-pressed pin is that of a buffer to take the shock of the tool carrier 20 as it springs back into the recess 38 after being given a half rotation.

10 It is desirable in a machine of the class herein described that the operator should have a support for the sole of a shoe to assist him in holding the shoe accurately in position during the burnishing of the edge 15 of the sole and in the corrugating of the same. Otherwise the shoe is held, as it were, in the air and there is nothing to guide the operator other than the burnishing tool itself which, of course, is a rapidly moving 20 piece and forms a very poor guide in positioning the shoe. The shoe should be positioned independently of the burnishing tool and the burnishing tool allowed to perform its function, which is that of setting and 25 burnishing the edge of a sole. I have, therefore, provided a presser foot 65 (see Figs. 2 and 3). This presser foot consists, as a whole, of a plate 66 pivoted at 67 to a carrier 68 which, in turn, is pivoted at its 30 lower end at 69 to a holder 70. A spring 71 is fastened at its lower end to the carrier 68 and bears at its free upper end against the lower free end of the plate 66, thus holding said plate with a yielding pres- 35 sure against the tread of the sole of the shoe being operated upon. A screw 72 having screw-threaded engagement with the holder 70 bears at its outer end against the carrier 68, thus governing the relative pos- 40 ition of the carrier and the holder. The holder 70 and the carrier 68 form, as a whole, a support upon which the presser foot plate 66 is pivoted.

The holder 70 has a shank 73 thereon 45 which is mounted to slide in a boss 74 provided on a bracket 75 fast to the frame of the machine and said shank 73 is fastened to the boss 74 by a set-screw 76 so that the holder 70 and the parts supported directly 50 and indirectly thereon, may be moved toward or away from the shoe 77 to bring the presser foot plate 66 in proper relation to the sole of the shoe being operated upon, whatever may be the shape or style of said 55 shoe and when so properly placed with relation to the shoe and to the edge burnishing tool the presser foot, as a whole, is held firmly in position by tightening the set-screw 76.

60 The rocker frame 16 is adapted to slide upon the shaft 17 longitudinally thereof or in a plane extending transversely of the working face of the edge setting tool 23 and a spring 78 is fastened at one end thereof to 65 the frame 18. At the other end thereof said

spring is fastened to a plate 79 which is adjustably fastened to the rocker frame 16 by means of a set-screw 80 which projects through a slot 81 in said plate and has screw-threaded engagement with said rocker 70 frame. This spring 78 may be utilized to push the rocker frame 16 forward or to pull it back under normal conditions, as, for example, by setting the plate 79 toward the left (Fig. 2) the spring 78 will be brought 75 under compression and will thus force the rocker frame 16 toward the right; or, on the other hand, by setting said plate 79 toward the right the spring 78 will be brought under tension and the rocker frame 16 will 80 be drawn normally toward the left, as illustrated in Fig. 2. The limit to which the rocker frame 16 can be moved toward the right (Fig. 2) is regulated by a collar 85 which is fastened to the shaft 17. The ob- 85 ject of this construction is so that the operator can hold the tread of the sole of the shoe against the presser plate 66 and, tipping the shoe transversely thereof, can bring the upper edge against the corrugating 90 wheel 25, thus moving the rocker frame 16 slightly along the shaft 17 and the tension of the spring 78 will then be applied to pressing the corrugating wheel firmly 95 against the upper edge of the sole being 100 operated upon, and thus the impressions of the corrugating wheel upon the upper edge of the sole will be clear and distinct, independent of any slight variations that there may be in the surface of the upper edge of 105 said sole. During this operation of burnishing and corrugating the edge of the fore part of the sole of the shoe, the operator to steady his hand and enable him to accurately locate the shoe and hold it in position during said operation of burnishing and corrugating passes the index finger of his left hand around the downwardly projecting arm 82 of the holder 70, this downwardly extending portion thus constituting 110 a finger rest.

It will be understood that the presser foot hereinbefore described is used only when the fore part of the sole is being operated upon and when the shank portion is being operated upon said presser foot does not engage the sole of the shoe. This result is accomplished by locating the work rubbing surface of the shank burnishing tool at a greater distance from the median axial line of the shank 21 of the tool carrier than is the work rubbing surface of the burnishing tool 23 and also by placing the shank burnishing tool at an angle to the median axial line of the shank 21, and the operator by tipping the shoe at a corresponding angle causes the sole in the shank portion thereof to clear the presser foot when the shank portion is being operated upon.

Suitable gas pipes 83 and 84 are provided 130

for directing a flame against the burnishing irons to keep the same heated.

After the edges of the sole of the shoe have been burnished and corrugated, as hereinbefore described, the same are subjected to the polishing action of a conveniently located brush 86 which rotates upon a shaft 87 and has a rotary action imparted thereto by a pulley 88, belt 89 and pulley 90. The pulley 90 is rotatably mounted upon a counter-shaft 91 and is rotated by means of a pulley 92 and belt 93.

The general operation of the mechanism hereinbefore specifically described and illustrated in Figs. 1 to 8, inclusive, is as follows: The operator places the shoe with the tread of the sole bearing against the presser foot plate 66 and holds the edge of the same firmly against the working face of the burnishing iron 23, turning the same longitudinally of the shoe in order to bring said burnishing tool in contact with all portions of the edge of the fore part of the sole. At the same time he tips the shoe transversely thereto of slightly and causes the corrugating wheel 25 to be pressed into the upper edge of the sole, while at the same time, using the presser foot plate as a pivot, he pulls the rocker frame 16 forward, placing the spring 78 under tension, and thus the edge of the sole of the shoe is set or burnished and the upper edge of the sole is corrugated.

When the fore part has been finished the operator presses his knee against the knee piece 43, rocking the lever 34 and moving the holder 50 upon its pivot to bring the cam finger 55 in alignment with the roll 30. Upon further movement of the lever 34 the iron 24 takes the place of the iron 23, as hereinbefore described and the operator then holds the edge of the shank portion of the sole of the shoe against the iron 24 to burnish said shank portion.

While burnishing the edge of the fore part of the shoe the operator steadies his hand, as hereinbefore described, by passing the index finger of his left hand around the downwardly extending portion 82 of the holder 70. When he is burnishing the shank portion he steadies his hand by passing the thumb of his left hand over the rest-rod 94 which is supported upon the bracket 75.

In cases where the fore part burnishing iron is used without the corrugating wheel 25 and where it is desired to burnish not only the edge of the sole, but that portion of the tread immediately adjacent to the edge of the sole, the spring 78 is placed under compression, as hereinbefore described, and in that case the rocker frame 16 is pushed by said spring outwardly against the collar 85. Then when the edge of the sole is placed against the burnishing iron the operator can push the same away from him or toward the left (Fig. 2), thus bringing the tread por-

tion of the sole immediately adjacent to the edge thereof into contact with the burnishing iron, and by pressing thereagainst the burnishing iron will rub or burnish the tread of the sole immediately adjacent to the edge with a yielding pressure caused by the spring 78 being under compression.

In Figs. 9, 10 and 11 modifications of my improved presser foot are illustrated. Referring to these figures it will be seen that in Fig. 9 the parts are substantially as in the presser foot illustrated in Figs. 2 and 3, except that a spring 95 is interposed between the holder 70 and the carrier 68 in lieu of the screw 72.

In Fig. 10 the presser foot plate 96 is extended downwardly and has a projection 97 fast thereto which bears against a spring 98 fast to the carrier 68, the carrier 68 being pivoted to the holder 70 as in the form illustrated in Figs. 2 and 3.

In Fig. 11 the presser foot plate 99 is pivoted directly to the holder 100 which constitutes a support therefor and the intermediate plate 68 is omitted. A spring 101 is fastened to the holder 100 and bears at its free end against the free end of the presser foot plate 99.

The form of presser foot illustrated in Fig. 9 differs from that illustrated in Figs. 2 and 3 by having a yielding member interposed between the holder 70 and the carrier 68 to regulate the relative positions of these parts. The presser foot illustrated in Fig. 10 differs from the presser foot illustrated in Figs. 2 and 3 and the form illustrated in Fig. 9 in that the presser foot plate is extended downwardly and bears against a spring located at the lower end of the intermediate or carrier plate 68, thus supporting the shoe nearer the lower edge as it is held against the burnishing tool than is the case in either of the other forms referred to.

The form illustrated in Fig. 11 is a simplified form similar in its character and results to the form illustrated in Figs. 2 and 3, but with the intermediate carrier plate omitted.

In the drawings, the corrugating wheel is illustrated with its corrugations of such length as to corrugate that portion of the upper face of the sole immediately adjacent to the edge. It is evident, however, that the corrugations may be of such length, or the projection of the sole beyond the upper of such an extent, that said corrugations will cover the entire visible portion of the upper face of the sole or of the welt which forms, in effect, a portion of said sole.

In the foregoing specification I have described how the outer edge of the sole may be set or burnished and the upper edge of the sole corrugated. I have also described

how the outer edge of the sole can be burnished and the portion of the tread of the sole immediately adjacent to the outer edge thereof simultaneously burnished. It is, however, possible and practicable to burnish or set the outer edge of the sole and also to burnish the tread of the sole adjacent to the outer edge and to simultaneously corrugate the upper edge of the sole adjacent to said outer edge in the machine of my invention by using an iron with a corrugating wheel so placed thereon and of such dimensions that the sole will be a tight fit in the space between the corrugating wheel and the downwardly projecting lip on the burnishing iron. By using an iron in which the edge of the sole is a tight fit, as hereinbefore set forth, it will be evident that the outer edge of the sole can be burnished or set and simultaneously the upper edge of the sole can be corrugated by the corrugating wheel 25, while the portion of the tread of the sole adjacent to the outer edge thereof will be burnished by the downwardly projecting lip or guard 23' of the burnishing iron. This possibility of burnishing the outer edge of the sole and the tread of the sole adjacent to said outer edge and corrugating the upper edge of the sole simultaneously by means of my improved machine may be clearly seen by reference to Figs. 9, 10 and 11, in which the sole is shown as fitting closely in the channel of the burnishing iron and between the corrugating wheel 25 and the downwardly projecting lip or guard 23'.

Having thus described my invention, what I claim and desire by Letters Patent to secure is:

40 1. A machine for burnishing the edges of the sole of a boot or shoe having, in combination, a tool carrier, an edge setting tool mounted on said carrier, means to impart movement to said edge setting tool and a presser foot embodying a support and a plate adapted to bear against the tread of said sole, one end of said plate being pivoted to said support.

50 2. A machine for burnishing the edges of the sole of a boot or shoe having, in combination, a tool carrier, an edge setting tool mounted on said carrier, means to impart movement to said edge setting tool, a presser foot embodying a support and a plate adapted to bear against the tread of said sole, one end of said plate being pivoted to said support and a spring interposed between said support and the free end of said plate.

55 3. A machine for burnishing the edge of the sole of a boot or shoe having, in combination, a tool carrier, an edge setting tool mounted on said carrier, means to impart motion to said edge setting tool, a presser foot embodying a support in two parts, one pivoted to the other, and a plate adapted to

bear against the tread of said sole, one end of said plate being pivoted to one of said parts.

4. A machine for burnishing the edge of the sole of a boot or shoe having, in combination, a tool carrier, an edge setting tool mounted on said carrier, means to impart motion to said edge setting tool, a presser foot embodying a support in two parts, one pivoted to the other, a plate adapted to bear against the tread of said sole, one end of said plate being pivoted to one of said parts and a spring interposed between one of said parts and the free end of said plate.

5. A machine for burnishing the edge of the sole of a boot or shoe having, in combination, a tool carrier, an edge setting tool mounted on said carrier, means to impart motion to said tool, a presser foot embodying a support in two parts, namely, a holder and a carrier, said presser foot carrier being pivoted to said holder, and a plate adapted to bear against the tread of said sole, the upper end of said plate being pivoted to the upper end of said carrier.

6. A machine for burnishing the edge of the sole of a boot or shoe having, in combination, a tool carrier, an edge setting tool mounted on said carrier, means to impart motion to said tool, a presser foot embodying a support in two parts, namely, a holder and a carrier, said presser foot carrier being pivoted to said holder, a plate adapted to bear against the tread of said sole, the upper end of said plate being pivoted to the upper end of said carrier, and a spring interposed between said presser foot carrier and the free end of said plate.

7. A machine for burnishing the edge of the sole of a boot or shoe having, in combination, a tool carrier, an edge setting tool mounted on said carrier, means to impart motion to said tool, a presser foot embodying a support in two parts, namely, a holder and a carrier, said presser foot carrier being pivoted to said holder, means interposed between said holder and presser foot carrier adapted to govern the relative position of said parts, a plate adapted to bear against the tread of said sole, the upper end of said plate being pivoted to the upper end of said carrier and a spring interposed between said presser foot carrier and the free end of said plate.

8. A machine for burnishing the edge of the sole of a boot or shoe having, in combination, a rocker frame, mechanism adapted to impart a rocking motion thereto, a tool carrier mounted on said rocker frame, an edge setting tool mounted on said carrier and a presser foot adapted to bear against the tread of said sole, said rocker frame adapted to slide in a plane extending transversely of the working face of said edge setting tool.

9. A machine for burnishing the edge of the sole of a boot or shoe having, in combination, a rocker frame, mechanism adapted to impart a rocking motion thereto, a tool carrier mounted on said rocker frame, an edge setting tool mounted on said carrier, a presser foot adapted to bear against the tread of said sole, said rocker frame adapted to slide in a plane extending transversely of the working face of said edge setting tool and a spring connected to said rocker frame and to a stationary support, whereby said rocker frame may be moved, by means of said sole, against the action of said spring. 10. A machine for burnishing the edge of the sole of a boot or shoe having, in combination, a rocker frame, mechanism adapted to impart a rocking motion thereto, a tool carrier mounted on said rocker frame, an edge setting tool mounted on said carrier, a presser foot adapted to bear against the tread of said sole, said rocker frame adapted to slide in a plane extending transversely of the working face of said edge setting tool, a spring connected to said rocker frame and to a stationary support, whereby said rocker frame may be moved, by means of said sole, against the action of said spring and a stop to regulate the extent of such movement. 11. A machine for burnishing the edge of the sole of a boot or shoe having, in combination, a rocker frame, mechanism adapted to impart a rocking motion thereto, a tool carrier mounted on said rocker frame, an edge setting tool mounted on said carrier, a corrugating wheel rotatably mounted on said edge setting tool and adapted to bear against the upper edge portion of said sole and a presser foot adapted to bear against the tread of said sole, said rocker frame adapted to slide in a plane extending transversely of the working face of said edge setting tool. 12. A machine for burnishing the edge of the sole of a boot or shoe having, in combination, a rocker frame, mechanism adapted to impart a rocking motion thereto, a tool carrier mounted on said rocker frame, an edge setting tool mounted on said carrier, a presser foot adapted to bear against the tread of said sole, said rocker frame adapted to slide in a plane extending transversely of the working face of said edge setting tool, and a spring, one end of said spring being connected to the frame of said machine and the other end being adjustably connected to said rocker frame. 13. A machine for burnishing the edge of the sole of a boot or shoe having, in combination, a tool carrier, an edge setting tool mounted on said carrier, means to impart motion to said tool, a presser foot embodying a support in two parts, namely, a holder with a downwardly projecting arm adapted to form a finger rest, and a carrier, said presser foot carrier being pivoted to said holder, and a plate adapted to bear against the tread of said sole, the upper end of said plate being pivoted to the upper end of said carrier. 14. A machine for burnishing the edges of the soles of boots and shoes having, in combination, a rocker frame, a tool carrier adapted to be reciprocated thereon, a spindle adapted to be reciprocated upon a stationary support, a pinion fast to said spindle, a connection between said spindle and tool carrier, a slide, a rack fast to said slide and normally out of alignment with and out of engagement with said pinion, a holder pivoted to said slide, a lever connected to said holder and a cam-shaped finger fast to said holder adapted to engage said spindle and impart a reciprocatory motion thereto, whereby said rack and pinion may be brought into alignment and engagement with each other, and a rotary motion imparted to said spindle and tool carrier. 15. A machine for burnishing the edge of the sole of a boot or shoe having, in combination, a rocker frame, a tool carrier rotatable thereon, mechanism adapted to reciprocate and rotate said tool carrier, including a vertically extending lever, a sleeve rotatably and slidably mounted on said lever, means to lock said sleeve to said lever, means to prevent said sleeve from sliding in one direction on said lever and a laterally extending arm pivoted to said sleeve adapted to be engaged by the knee of the operator. 16. A machine for burnishing the edge of the sole of a boot or shoe having, in combination, a rocker frame, a tool carrier rotatable thereon, mechanism adapted to reciprocate and rotate said tool carrier, including a vertically extending lever, a sleeve rotatably and slidably mounted on said lever, means to lock said sleeve to said lever, means to prevent said sleeve from sliding in one direction on said lever and a laterally extending arm pivoted to said sleeve adapted to be engaged by the knee of the operator, a flexible member fast to said arm and extending upwardly therefrom to said sleeve and a spring fast to said arm extending downwardly therefrom to said sleeve. 17. A machine for burnishing the edge of the sole of a boot or shoe having, in combination, a rocker frame, a tool carrier rotatable thereon, mechanism adapted to reciprocate and rotate said tool carrier, including a vertically extending lever, a sleeve rotatably and slidably mounted on said lever, means to lock said sleeve to said lever, means to prevent said sleeve from sliding in one direction on said lever, a laterally extending arm pivoted to said sleeve adapt- 70 75 80 85 90 95 100 105 110 115 120 125 130

ed to be engaged by the knee of the operator, a collar adjustable longitudinally on said arm, a flexible member fast to said collar and extending upwardly therefrom to
5 said sleeve and a spring fast to said arm and extending downwardly therefrom to said sleeve.

In testimony whereof I have hereunto set my hand in presence of two subscribing witnesses.

ZOTIQUE BEAUDRY.
